UNITED STATES PATENT OFFICE.

SIGISMONDO GALLINA, OF HOBOKEN, NEW JERSEY.

KNEE BREECHES.

Application filed October 8, 1924. Serial No. 742,326.

My invention is adapted to be applied to riding breeches, golf pants, knickerbockers, and in fact various garments the legs of which reach somewhat below the knees. The object of my invention is to provide a garment of this type which when applied will fit snugly to the leg below the knee and which can be very quickly tightened or loosened upon the leg by the simplest kind of operation. Heretofore in garments of this kind, especially riding breeches, it has been common to close the bottom ends of the legs by means of laces interlaced through eyelets but the attachment of such devices is not only unreliable but the opening and closing of the bottom of the legs upon the wearer consume more time than is necessary with the present device. Other means of attachment, such as buttons, hooks and eyes, and the like, have been heretofore provided but these all have their disadvantages. With the present device the buttons of the legs may be closed or opened by simply moving a sliding member along the seam of the garment so that the opening and closing operations are almost instantaneous and may be easily performed by the wearer without even having to look at the device, so that the latter may be operated in the dark if desired. I have provided a novel arrangement of elastic and pleat for allowing for variations in leg sizes as the attachment means itself is not susceptible to adjustment.

In the drawing forming part of this application,

Figure 1 is a front elevation of a pair of riding breeches having my invention applied thereto,

Figure 2 is an elevation on an enlarged scale of the lower end of one of the legs looking at the side thereof, and

Figure 3 is a sectional view taken on the line 3—3 of Figure 2.

In the drawing I have shown a pair of riding breeches 1 having a waist band 2 and hip portion 3 below which are the legs 4. The latter are adapted to extend below the knee and at the lower ends they are provided with the improved closing means. Both legs of the garment are provided with similar closing devices so that the same description will apply to both. There is generally a seam 5 extending down the side of the garment and with garments of the character herein set forth this seam generally

ends at the bottom at about the point 6 which will come just below the knee of the wearer. From this point the leg is provided with a side opening 7 or placket which extends down to the bottom end of the leg. The purpose of this side opening or placket, as is well known, is to permit the bottom of the leg to open or expand in order to allow the wearer to pass his or her shoe through the leg of the garment, and especially through the narrow, lower end of the garment leg. In garments of the types referred to, it is desirable to close this side opening or placket to make the lower end of the garment leg fit snugly to the leg just below the knee.

In the drawing I have shown a closing device which in itself is not new in the present case as it is the combination which forms the subject of the present invention. The placket closing device comprises in part a strip or tape 8 secured, preferably by a line of stitches 9 along one of the edges 10 of the leg of the garment which forms one side of the placket. To this tape are fastened a row of metal members 11 having small interlocking hooks 12 all spaced equal distances apart throughout the length of the tape 8, which is preferably the length of the side opening or placket. To the opposite edge 13 of the fabric defining the opposite side of the placket, there is attached, preferably by means of a line of stitches 14, another band or tape 15 to which is permanently secured a row of metal members 16 which are spaced apart to correspond with the spacing of the several members 11. These members 16 are also provided with hooks 17 which are adapted to interlock with the hooks 12 of the members 11. The tapes 8 and 15 and the rows of hooked members extend from the point 6 at the bottom of the seam 5 to the bottom end of the leg of the garment.

The opposite rows of hooked members are adapted to be locked and unlocked by means of a slider 18 which straddles the opposite rows of hooked members 11, 16 and which is adapted to be moved along the rows of hooked members. There is a pivoted finger piece 19 which may be grasped to operate the slider.

When the slider 18 is in its upper position, that is, at the top of the placket, the two rows of hooked members 11, 16 are unlocked or disengaged and the bottom of the garment

leg may open or expand to allow the wearer to put his or her foot therethrough. When the garment has been put on by the wearer, the finger piece 19 is grasped and the slider 5 is moved downwardly along the rows of hooked members and when this occurs the opposite rows of hooked members are drawn toward each other by the slider and the hooks 17 are caused to interlock with the 10 hooks 12 so that the edges of the leg of the garment are held in closed position. The slider remains at the bottom of the leg 4 while the garment is being worn and it may be covered by the stocking, puttee or boot. 15 Both plackets are closed in the manner just described. The edges of the garment are held closely together and are neater in appearance than where they are drawn together by laces. To open the plackets the sliders 20 are simply moved upwardly and they serve to unlock the hooks 17 from the hooks 12 as the slider moves along the rows of hooked members; and this releases the edges of the garment. These opening and closing operations 25 may be performed almost instantaneously. The type of fastener referred to herein is further shown and described in the U. S. patent to Judson No. 504,038 and No. 504,037 dated August 29th, 1893, and 30 No. 557,208 dated March 31st, 1896.

The closing devices allow no adjustment of the leg of the garment and I provide for this in the following manner. There is a strip 20 of elastic material or elastic webbing, which is stitched along one edge of the garment by a line of stitches 21 which is placed back away from the placket. The other edge of this elastic webbing is attached by the line of stitches 14 to the tape 15 and 35 to one of the edges 13 of the leg member 4. Between these lines of stitches 21, 14 or between the opposite edges of the elastic web-

bing 20 the material of the leg member 4 is made full to form a fold or plait 23. If the wearer should have a comparatively small 45 leg the elastic webbing 20 will not be stretched when the placket is closed but if the leg is relatively large in diameter, then when the placket is closed by the action of the slider and hooked members, the adjacent 50 edges of the placket being drawn together will cause the webbing 20 to be extended or drawn out any extent necessary up to the limit permitted by the straightening out of the fabric in the plait 23. The elastic and 55 plait, therefore, permit the bottom of the leg of the garment to be expanded when necessary and at the same time insure a snug fit of the lower end of the leg of the garment.

Having described my invention, what I 60 claim is:

A garment of the class described having leg members adapted to extend below the knees of the wearer, each leg member having a vertically extending opening or placket at 65 the lower end thereof, means for drawing the edges of the placket together, comprising a row of hooked members secured along the edges of the garment defining said placket, said hooked members of the two rows being 70 adapted to be interlocked and to be disengaged, a slider movable along said rows of hooked members and adapted to cause said hooked members to be interlocked and to disengage, and an elastic member secured to 75 one of the edges of the placket and secured to the leg member at a point spaced from said first place of attachment, said leg member having a loop or plait formed between the points of attachment of said elastic member 80 when the latter is contracted.

Signed at the city, county and State of New York, this 20th day of September, 1924.

SIGISMONDO GALLINA.
